JOINT FOR CONCRETE STRUCTURES

Alexander Tate, Fareham, England

Application July 15, 1941, Serial No. 402,521
In Great Britain March 1, 1941

3 Claims. (Cl. 72—106)

This invention relates to joints for concrete structures, and has for its principal object to provide improved jointing means for preventing leakage of moisture between contacting surfaces of adjacent structural slabs or blocks of concrete, imitation stone, or other plastic material capable of setting to a hard mass and which may contain sand or coarse or fine aggregate, all deemed to be included herein in the term "concrete."

It is another object of the invention to provide improved means for waterproofing such joints whilst also allowing for the contraction of the slabs or blocks of concrete on setting to the hard condition and any further alteration due to temperature changes. The word "waterproofing" is to be understood to include proofing against liquids other than water.

Hitherto it has been the practice to embed a metal jointing strip in the concrete of the adjacent slabs or blocks during construction, this strip extending, where practicable, for the full length of the joint, and usually having a ripple or corrugation to allow for shrinkage of the slabs on setting or expansion or contraction thereof due to temperature or other changes.

This type of joint seal, however, has the disadvantage that, unless special precautions are taken, the contraction of the concrete on setting may loosen the jointing strip and so destroy the waterproofing quality of the seal. Moreover, in the event of damage to or failure of the seal, considerable difficulty and labour are involved in its replacement. It is also to be noted that as a joint seal of such type requires the metal jointing strip to be embedded during formation of the concrete slabs or blocks the strip is exposed to risk of damage by workmen engaged in the pouring of the concrete and in the dismantling or erection of shuttering or formwork used for outlinning or forming the adjacent slabs or blocks. Furthermore, such a seal cannot be employed when precast concrete slabs are used for the structure.

An important object of the present invention is to overcome these difficulties and to provide an improved waterproof seal for joints in concrete structures which is of very highly reliable character and construction.

A more specific object is to provide for sealing a joint between two concrete slabs or blocks, a channel formed partly in one slab or block and partly in the other and extending lengthwise of the joint, slots extending in each slab or block from said channel, bolts placed in said slots,

strips of sealing material placed about said bolts along the side walls of said channel, a jointing strip disposed in said channel and having lateral edges engaged over said bolts and with said sealing strips, and clamping bars secured by the bolts against said lateral edges.

Yet another more specific object is to provide, for sealing a joint between two concrete slabs or blocks, a channel formed partly in one slab or block and partly in the other and extending lengthwise of the joint, slots extending in each slab or block from said channel, a first series of bolts placed in said slots, a second series of bolts secured in the slabs or blocks adjacent said channel and with their axes at right angles to those of the first series of bolts, strips of sealing material placed about the bolts of each of said series, a jointing strip extending longitudinally of said channel and engaged adjacent its lateral edges over both said series of bolts, and with said sealing strips, and clamping bars secured by said series of bolts against said lateral edges.

Yet other objects will be understood from the following description of suitable forms of waterproof joint seals according to the invention and which, given purely by way of example, are shown in the accompanying drawings, wherein:

Fig. 1 depicts part of a concrete structure embodying concrete slabs or blocks and having applied to the joint between the slabs or blocks a joint seal in accordance with the present improvements.

Fig. 2 is a transverse section taken on the line II—II of Fig. 1;

Fig. 3 is a section on the line III—III of Fig. 1;

Fig. 4 is a half-view taken similarly to Fig. 2, and showing a second form of seal; and

Fig. 5 is a view similar to Fig. 4 showing a modified form of seal;

In Figures 1 to 3, which may be regarded as illustrating the waterproofing of the joint between slabs or blocks of a concrete structure such as a wall or floor. The joint seal is applied at a recess or channel 1 formed in the surface of ad-

45 jacent slabs or blocks 2, 3 and extending lengthwise of the joint 4 between the slabs. The channel is located half in one slab and half in the other and, of course, extends the whole length of the joint between the slabs, though it has only been necessary to show a part of the slabs in Figure 1 for purposes of illustration. At intervals along the channel, the slabs are formed with transverse slots 5 of less depth than the channel and extending at right-angles thereto from its side walls. These slots extend to open recesses

6 (of greater width and depth than the slots) which are formed in the slabs to accommodate the heads 7 of a series of bolts 8 whose shanks are laid in the slots 5 with a large rectangular washer 9 mounted beneath each bolt head 7 and eccentrically drilled so that its lower edge reaches almost to the bottom of the corresponding recess.

In rendering the joint 4 between the slabs waterproof, the bolts 8 are inserted into all the slots 5 on both sides of the channel 1 as soon as desired after removal of the shuttering or form-work used in casting the slabs. On each side of the channel, a strip 10 of resilient or compressible sealing material, for example rubber, is mounted about the threaded ends of the bolts 8. Also a jointing strip 11 of metal or other suitable material and having a central longitudinal ripple or corrugation 12 formed therein is laid along the floor of the channel 1 outside of the joint 4 and has its marginal edges bent at right angles to lie close to the side walls of the channel. By means of holes previously drilled therein, the strip 11 is engaged by the threaded ends of the bolts 8, and a rigid compression bar 13 of metal or other suitable material, also ready drilled for the purpose, is placed over the bolts to press upon the jointing strip 11. A nut 14 is then threaded onto each bolt, with or without the interposition of a locking or other washer 15, and drawn up tightly to clamp the jointing strip 11 firmly between the compression bar 13 and the strip of sealing material 10, the latter being also forced into intimate sealing contact with the side walls of the channel 1. In this way the joint 4 is completely sealed against leakage from the inside or the outside of the structure and contraction and/or settling of the adjacent slabs 2, 3 on hardening is accommodated by the ripple 12 in the jointing strip 11. Finally, the recesses 6 in which lie the bolt shanks, are filled with cement mortar or the like.

In the second form of seal illustrated by Fig. 4, the marginal edges of the jointing strip 11 are extended, as at 11a, to lap over the outer edge of each channel side wall for a sufficient distance to permit of a second strip 16 of sealing material to be inserted beneath each jointing-strip part 11a, and a second compression bar 17, mounted on bolts 18 of a second series which are embedded in each slab 2, 3 is clamped down on each slab by nuts 19 threaded onto the embedded bolts after the slots 5 and recesses 6 have been filled as aforesaid and the mortar has set therein. These bolts 18 are preferably located midway between adjacent bolts 8. In this way, two water-tight seals are formed in planes at right angles to each other, and are arranged in series with respect to the path of leakage of moisture through the joint 4 between the slabs 2, 3.

The joint seal shown in Figure 5 comprises a modified form of compression bar comprising a length of angle iron 20. Such a bar has greater rigidity, and enables fewer bolts to be used.

Joint sealing and waterproofing means according to the invention may be employed with particular advantage, in reservoirs and tunnels. In the latter application, the channels 1 in con-

structions such as are shown in Figs. 1-4, would generally be on the inside of the tunnel and could be used as conduits to carry lighting cables or other services. Where the channels are used in reservoirs they may accommodate any piping or such other form of service apparatus as may be required. Any of the forms of joint seal described or illustrated may be used for sealing joints in walls, floors, roofs and arches. It will further be understood that the composition or character of the jointing strips and the compression bars will be selected according to the conditions of service to be encountered. Normally, the metallic parts will be of steel coated with paint where exposed to the water or liquids or to the atmosphere, but, if desired, copper or brass, other alloys, or plated or anodised parts may be used. It will be noted, however, that in each construction the ripples or corrugations extend in a direction away from the concrete and that the strip 11 is completely outside of the joint and thus unaffected by movements in the joint.

Obviously, there may be more than one of such ripples or corrugations in the strips 11, such as two running parallel to each other one on each side of the longitudinal centre line of the strips.

What I claim is:

1. For sealing a joint between two concrete slabs or blocks, a channel formed partly in one slab or block and partly in the other and extending lengthwise of the joint, slots extending in each slab or block from said channel, bolts placed in said slots, strips of sealing material placed about said bolts along the side walls of said channel, a jointing strip disposed in said channel and having lateral edges engaged over said bolts and with said sealing strips, and clamping bars secured by the bolts against said lateral edges.

2. For sealing a joint between two concrete slabs or blocks, a channel formed partly in one slab or block and partly in the other and extending lengthwise of the joint, slots extending in each slab or block from said channel, a first series of bolts placed in said slots, a second series of bolts secured in the slabs or blocks adjacent said channel and with their axes at right angles to those of the first series of bolts, strips of sealing material placed about the bolts of each of said series, a jointing strip extending longitudinally of said channel and engaged adjacent its lateral edges over both said series of bolts, and with said sealing strips, and clamping bars secured by said series of bolts against said lateral edges.

3. For sealing a joint between two concrete slabs or blocks, a channel formed partly in one slab or block and partly in the other and extending lengthwise of the joint, slots extending in each slab or block from said channel, bolts placed in said slots, strips of sealing material placed about said bolts along the side walls of said channel, a jointing strip disposed in said channel and having lateral edges engaged over said bolts and with said sealing strips, and angle-section clamping bars secured by the bolts against said lateral edges.

ALEXANDER TATE.
